UNITED STATES PATENT OFFICE.

JESSE H. BUNNELL, OF NEW YORK, N. Y.

DESIGN FOR A SOFA.

SPECIFICATION forming part of Design No. 29,640, dated November 8, 1898.

Application filed October 17, 1898. Serial No. 693,831. Term of patent 7 years.

To all whom it may concern:

Be it known that I, JESSE H. BUNNELL, a citizen of the United States, residing at New York, (Brooklyn,) in the county of Kings and State of New York, have invented and produced a new and original Design for Sofas, of which the following is a specification, reference being had to the accompanying drawing, which is a perspective view showing my design.

As shown in the drawing, the leading or material feature of my design consists of a sofa having curvilinear backs A A' at its opposite ends and a straight back A² intermediate said ends, with curvilinear depressions b b² between the straight back and the cur-

vilinear backs and corresponding curvilinear arms or ends a a', with legs L L at the ends of the sofa and intermediate legs L' L' L² L².

Having thus described my invention, what I claim as new, and desire to secure by Letters Patent of the United States, is—

The design for a sofa as herein shown and described.

In testimony whereof I have hereunto subscribed my name this 15th day of October, 1898.

JESSE H. BUNNELL.
